G. E. HUNTER.
MECHANISM FOR SETTING WATCH JEWELS.

No. 503,483.

Patented Aug. 15, 1893.

George E. Hunter, by
Crandall and Russell, his Attorneys.

UNITED STATES PATENT OFFICE.

GEORGE E. HUNTER, OF ELGIN, ASSIGNOR TO THE ELGIN NATIONAL WATCH COMPANY, OF CHICAGO, ILLINOIS.

MECHANISM FOR SETTING WATCH-JEWELS.

SPECIFICATION forming part of Letters Patent No. 503,483, dated August 15, 1893.

Application filed August 22, 1892. Renewed July 19, 1893. Serial No. 480,953. (No model.)

To all whom it may concern:

Be it known that I, GEORGE E. HUNTER, of Elgin, in the county of Kane, and in the State of Illinois, have invented certain new and useful Improvements in Mechanism for Setting Watch-Jewels; and I do hereby declare that the following is a full, clear, and exact description thereof, reference being had to the accompanying drawings, in which—

10 Figure 1 is a perspective view of the jewel holding tube separated from the other parts. Fig. 2 is a like view of the detents separated from the tube. Fig. 3 is a perspective view of the spring actuated follower. Fig. 4 is a 15 central longitudinal section of the tube and its connecting parts and shows the detents separated to permit the jewels to escape. Fig. 5 is a detail view of guard plate G.

Letters of like name and kind refer to like 20 parts throughout the several figures.

The object of my invention is to enable watch jewels to be automatically fed into a setting, and to such end my invention consists in the construction of the holding mechanism, substantially as and for the purpose 25 hereinafter specified.

In the carrying of my invention into practice, I employ a tube A which has such diameter of interior as will permit of the ready insertion 30 therein of a series of jewels B and B having the desired diameter. At its outer end said tube is inclosed by means of a number of spring detents C and C that normally occupy a closed position and prevent the outward 35 passage of jewels, but may when desired, be moved radially outward so as to leave the outer end of said tube free. The inner or rear end of the tube A is closed and within the interior is placed a follower D that loosely fills 40 the same laterally, and by means of a spring E, which is placed between its rear end and the rear end of said tube operates to hold such jewels as are placed at its front with a yielding pressure against the detents C and C. In 45 the use of the jewel holding tube, it is inserted into and locked within a suitable supporting part F which part is provided with an outwardly and forwardly inclining surface that engages oppositely inclined faces c and c which are provided upon the projecting ends 50 of the detents C and C and operate to spread

the latter apart just as the tube reaches position within said supporter. In order that when the detents are spread apart the jewels may not escape there is provided in front of 55 the tube A a swinging or rotary guard plate G which is held in position in front of said tube by means of a spring and when pushed to one side so as to uncover the latter automatically returns to place when released. 60

To set a jewel, the setting is formed upon the end of a rod and is then moved in front of the tube A and in a line axially therewith. When thus moved to position said setting, or its holder, engages with and moves the guard 65 plate G to one side so that when the axes of said setting and tube coincide, a jewel will be pressed outward into the opening in the former.

Having thus described my invention, what 70 I claim is—

1. As an improvement in mechanism for mechanically setting jewels, a holder having a jewel receiving opening to receive and hold a number of jewels, and a detent, or stop, 75 movable into and out of the path of a jewel in making its exit from said opening substantially as and for the purpose specified.

2. As an improvement in mechanism for mechanically setting jewels, a holder having 80 a longitudinal passage or chamber to receive and hold a number of jewels in line with each other, and a detent that normally prevents the exit of such jewels, substantially as and for the purpose shown. 85

3. As an improvement in mechanism for mechanically setting jewels a holder, having a longitudinal, jewel-receiving opening for holding a number of jewels and at one end several spring actuated detents that normally 90 extend over the opening to prevent the exit of a jewel, substantially as and for the purpose set forth.

4. As an improvement in mechanism for mechanically setting jewels, a holder having 95 a longitudinal jewel receiving opening and several spring actuated detents that normally extend over the opening, each of which has an abrupt inner face, and a beveled outer face, substantially as and for the purpose described. 100

5. As an improvement in jewel setting mech-

- anism, a holder having a passage to receive and contain a number of jewels that is normally closed against the exit of jewels, and is adapted to be automatically opened, and 5 means to cause the exit of a jewel when it is opened, substantially as and for the purpose specified.
6. As an improvement in jewel setting mechanism, the combination of a jewel holder having its jewel exit barred by a detent or stop movable into and out of the path of a jewel a support for such holder adapted to engage and hold said detent out of the path of a jewel, substantially as and for the purpose shown.
- 15 7. As an improvement in jewel-setting mechanism, the combination of a jewel holder having its jewel exit barred by a detent or stop movable into and out of the path of a jewel, a support for said holder to engage and hold 20 said detent or stop out of such path, and a second movable detent or stop adapted to prevent the exit of a jewel after said first named detent has been moved to allow it, substantially as and for the purpose set forth.

8. As an improvement in jewelsetting mech- 25 anism, the combination of a jewel holder having its jewel exit barred by a detent or de- tents, each of which has a beveled face, a sup- 30 port for such holder having a projection to engage the beveled faces of said detents, sub- stantially as and for the purpose described.

9. As an improvement in jewel setting mech- 35 anism, the combination of a jewel holder having its jewel exit barred by a detent or de- tents, each of which has a beveled face, a sup- 40 port for such holder having a projection to engage the beveled faces of said detents, and a movable plate adapted to cover and uncover the jewel exit, substantially as and for the purpose specified.

In testimony that I claim the foregoing I have hereunto set my hand this 17th day of June, 1892.

GEORGE E. HUNTER.
